UNITED STATES PATENT OFFICE.

JOSEPH L. HENRY, OF ROCHESTER, NEW YORK.

THILL-COUPING.

No. 814,005.

Specification of Letters Patent

Patented Feb. 27, 1906.

Application filed February 20, 1905. Serial No. 246,387.

To all whom it may concern:

Be it known that I, JOSEPH L. HENRY, a citizen of the United States, residing at Rochester, in the county of Monroe and State of New York, have invented certain new and useful Improvements in Thill-Couplings; and I do hereby declare the following to be a full, clear, and exact description of the invention, such as will enable others skilled in the art to 5 to which it appertains to make and use the same.

My invention has for its object to provide an improved coupling for thills, poles, &c.; and to this end it consists of the novel devices 15 and combinations of devices hereinafter described, and defined in the claims.

The improved coupling is illustrated in the accompanying drawings, wherein like characters indicate like parts throughout the several views.

Figure 1 is a view principally in side elevation, but with some parts sectioned, showing a portion of a pair of thills and the front axle of a vehicle, said parts being connected by 25 one of my improved couplings. Fig. 2 is a view, partly in side elevation, but with some parts sectioned, on the line $x^2 x^2$ of Fig. 3 and showing the thill detached from the coupling. Fig. 3 is a transverse vertical section taken 30 on the line $x^3 x^3$ of Fig. 1. Fig. 4 is a sectional view illustrating a modified form of the device, and Fig. 5 is a section on the line $x^5 x^5$ of Fig. 4.

The numeral 1 indicates a portion of the 35 thill, to which one of a pair of metallic straps 2 is rigidly secured in the ordinary or any suitable way—as, for instance, by a nutted bolt 3. The strap 2 at its projecting end terminates in a bearing-head 4, having an 40 open seat 5 extending downward and having at its top a notch or depression 6.

The numeral 7 indicates the front axle of a vehicle. This axle is provided with ordinary bifurcated thill-coupling brackets 8, which 45 are rigidly secured thereto in any suitable way—as, for instance, by means of co-operating yoke-clips 9, clamping-bars 10, and nuts 11. A stub-shaft or headless bolt 12 is loosely mounted in seats formed in the ears 50 of the coupling-bracket 8. This bolt in length is somewhat less than the distance from outside to outside of the two rears of said bracket.

The numeral 13 indicates a leaf-spring, one 55 end of which is rigidly secured to the axle, being, as shown, clamped between the bar 10

and one of the nuts 11. At its free end it is pivotally connected by a long spacing-rivet 14 to the lower ends of a pair of short metallic straps 15. The upper portions of these metallic straps 15 are bent outward, so that they closely embrace the outer surfaces of the ears of the coupling-bracket 8, and in line with the bolt 12 they are pivotally connected by rivets 16 to the depending prongs of a U-shaped lock-piece 17. The rivets 16 are provided with quite large heads, the inner of which are normally pressed into the outer extremities of the seats in which the bolt 12 is mounted. The lock-piece 17 is provided 70 with an upturned finger-piece 18 and with a downturned lock-foot 19, the end of which is adapted to engage with the lock-notch 6 of the strap 2 when the parts are in the position shown in Fig. 1.

When the thills are detached, as shown in Fig. 2, by taking hold of the lock-piece 17 and exerting considerable force tending to draw the same forward the inner heads of the rivets 16 may be sprung out of engagement with the seats in the coupling-bracket 8, and the straps 15 may be thus moved out of line with the bolt 12, so that the said bolt may be removed from working position or applied in working position by endwise movements. Normally, however, the spring tension of the prongs of the lock-piece 17 will hold the inner heads of the rivets in engagement with the seats in the coupling-bracket, thereby holding the bolt 12 in working position.

When the parts are adjusted as shown in Fig. 2, it is evident that the bifurcated head of the thill-strap 2 may be forced down onto the bolt 12 by a downward and slightly-rearward movement and may be locked to the bolt 12 with freedom for pivotal movements thereon by turning the lock-piece 17 forward, as shown in Fig. 1, thereby engaging the toe of the foot 19 with the lock-notch 6 of the strap-head 4. As is evident, when the parts are coupled as shown in Fig. 1 the lock-piece 17 is locked to the head 4 for pivotal movements with the thill-strap 2. It is further evident that when the parts are coupled as just noted 105 the spring 13 exerts a downward strain, which holds the lock-piece engaged with the notch 6 in the head of the strap 2, and, furthermore, that this downward strain takes up all slack between the parts and prevents 110 rattling thereof by holding the head 4 tightly pressed downward upon the bolt 12 and the

said bolt in turn tightly pressed down on its seats within the ears of the coupling-bracket 8.

In the modification illustrated in Figs. 4 and 5 a headed bolt 20 is passed through the ears of the coupling-bracket 8, through the prongs of the U-shaped lock-piece 17, and through the upper ends of the metallic straps 15. The perforations for the bolt in the straps 15 are vertically elongated, as indicated at 15^a, so as to permit limited movement of the straps and lock-piece, and thereby permitting the free engagement of the nose 19 of said lock-piece with the notch 6 of the detachable head 4 and likewise the disengagement of the said parts. This modified form of the coupling while within the broad scope of my invention is not the full equivalent of the form illustrated in Figs. 1, 2, and 3; but, on the contrary, the said construction illustrated in Figs. 1, 2, and 3 has points of superiority over the said construction illustrated in Figs. 4 and 5.

The coupling above described may be constructed at small cost, may be very easily and quickly manipulated, and is in all respects extremely efficient for the purposes had in view.

From what has been said it will be understood that the devices described are capable of modification within the scope of my invention as herein set forth and claimed.

What I claim, and desire to secure by Letters Patent of the United States, is as follows:

1. The combination with a coupling-bracket having laterally-spaced ears and a pivot-bolt extending between said ears, of a pair of laterally-spaced straps yieldingly supported at their lower ends, a lock-piece embracing the ears of said bracket, and pivotally connected to said straps in line with said pivot-bolt, and provided with a lock-foot, and a detachable member having a head formed with an open seat adapted to engage the pivot-bolt of said coupling-bracket, and which lock-foot is adapted to engage the head of said detachable member to hold the same interlocked with said lock-bolt, substantially as described.

2. The combination with a coupling-bracket having laterally-spaced ears and an endwise-removable bolt seated in said ears, of a leaf-spring secured at one end with respect to said bracket, laterally-spaced straps

connected to the free end of said spring and embracing the ears of said bracket, a yoke-like lock-piece pivoted to the ends of said straps and having a lock-foot, and a detachable member having a head formed with an open seat and with a lock-notch, which open seat is adapted to engage the bolt of said coupling-bracket, and which lock-notch is adapted to be engaged by the foot of said lock-piece, substantially as described. 55

3. The combination with a coupling-bracket having laterally-spaced ears and an endwise-removable bolt seated in said ears, of a leaf-spring secured at one end with respect to said bracket, laterally-spaced straps pivotally connected to the free end of said spring, with their upper ends embracing, and yieldingly held with respect to, the ears of said bracket, a yoke-like lock-piece, pivotally connected to the upper ends of said straps and having a lock-foot, and a headed member having an open seat and a lock-notch, which seat is engageable with the bolt of said bracket, and which lock-notch is adapted to be engaged by the foot of said lock-piece, substantially as described. 60 70 75

4. The combination with a coupling-bracket 8 having perforated ears, of a bolt 12 seated in said ears and extending less than completely through said ears, the spring 13 anchored at one end with respect to said bracket, the straps 15 pivotally connected to the free end of said spring and embracing the ears of said bracket, the yoke-like lock-piece 17 embracing the ears of bracket and provided with a finger-piece 18 and a lock-foot 19, rivets 16 pivotally connecting the prongs 90 of said lock-piece to the upper ends of straps 15, with their inner heads yieldingly held in engagement with the perforations in the ears of said bracket 8, and the member 2, having a head 4 formed with open seat 5 and lock-notch 6, which seat is engageable with said bolt 12, and which notch is adapted to be engaged by the foot of said lock-piece, substantially as described. 80 85 95

In testimony whereof I affix my signature in presence of two witnesses.

JOSEPH L. HENRY.
